UNITED STATES PATENT OFFICE

KARL E. JENSEN, OF CHICAGO, ILLINOIS, ASSIGNOR TO INDUSTRIAL GLOVES CORPORATION, OF CHICAGO, ILLINOIS, A CORPORATION OF DELAWARE

ARM PROTECTOR

Application filed May 20, 1929. Serial No. 364,492.

The invention relates generally to arm protectors and more particularly has reference to an arm protector especially adapted for use in connection with certain industries, such as the manufacture or fabrication of sheet metal, in which the workmen handle relatively rough, heavy articles having sharp cutting edges.

In producing an arm protector of this character, the general aim has been to devise a protector which combines the essential properties of being highly resistant to ordinary wear, as well as to cutting, tearing, and burning, with the additional advantageous properties of lightness, flexibility, porosity, and the absorption of perspiration.

More specifically, it is an object of the invention to provide an arm protector embodying an arm encircling base member of substantially light, flexible, relatively porous material, and an outer facing intimately secured to said base, formed of relatively heavy fibrous material, having a plurality of small metallic reinforcements dispersed about the entire surface thereof, and further including means for ventilating the protector during use.

A further object of the invention is to provide an arm protector having an arm encircling base formed of a material which is substantially pure wool, which base carries upon its exposed surface a reinforcing sheet of leather, or similar material, having closely spaced metallic reinforcements thereon.

Other objects and advantages will become apparent in the following description and from the accompanying drawings, in which:

Figure 1 is an elevational view of the arm protector upon a wearer's arm.

Fig. 2 is an extended plan view of the arm protector looking at the external side thereof.

Fig. 3 is a transverse section taken through the arm protector substantially along the lines 3—3 of Fig. 1.

In accomplishing the objects of the invention, I have produced an arm protector which will resist a great amount of wear and yet will be entirely comfortable to the wearer. It is essential that such a protector should

be capable of absorbing perspiration without subsequently becoming hard and inflexible, may be subjected to considerable heat without materially damaging the materials of which the protector is constructed, and does not materially hinder ventilation. Moreover, it is desirable that the protector be readily capable of being cleaned or sterilized.

Referring particularly to Fig. 2, of the drawings, a preferred construction of an arm protector which embodies these advantages is shown. The protector comprises a base 6 of sufficient length to encircle a wearer's arm and position the ends in overlapping relation, and is of any desired width depending upon the measure of protection which is to be afforded the wearer's arm.

At one edge of the base, a portion, indicated at 7, is folded backwardly upon itself and secured in this position by one or more rows of stitches 8. The edge thus reinforced constitutes that part of the protector which encircles the wearer's wrist, but, as may be seen in the drawings, it is preferred that the reinforcement extends along the edge only a sufficient distance to substantially encircle the wrist, whereby the reinforcement does not interfere with the pliability of that portion of the base, designated as 9, which is overlapped by the opposite side of the protector during use.

The preferred material, of which the base is constructed, is one or more sheets of wool felt composed of substantially pure wool fibers in their natural springy condition woven rather compactly together. Material of this nature is firm and strong and, due to the live springiness of the wool fibers, resists tearing and cutting to a marked degree. Moreover, this material is quite flexible and comfortable, is capable of absorbing large quantities of perspiration without becoming hardened or stiffened thereby, and may be washed, sterilized, or otherwise cleaned when necessary.

A reinforcing member 10 substantially covers that portion of the base 6 which is exposed when the protector is in use, and may be partially secured thereto by means of rows of marginal stitching 11. The reinforcing

member 10 is preferably formed of leather or a similar material which is resistant to wear, adds to the rigidity of the protector, and yet is somewhat flexible. Preferably the 5 member 10 is armored by a plurality of small, metallic staples 12, thickly dispersed about the surface thereof, in such manner that the flexibility of the member is not impaired. In consequence, the reinforcing member presents 10 an interrupted surface of metal, which is well adapted to resist the cutting, tearing actions of the sharp edges of the articles handled by the workmen. It is desirable, however, that the staples 12 extend only through the 15 reinforcing member so that the inner ends thereof rest against the felt base, thus preventing heat from being conducted through the protector to the wearer's arm.

Means are preferably provided for 20 ventilating the protector throughout the surface covered by the reinforcing member, a suitable form of which means comprises a number of spaced grommets or eyelets 13 extending through the base and reinforcing member, 25 and these grommets serve to secure the reinforcing member to the base should the stitching 11 break.

While any suitable means for securing the 30 arm protector in place upon the wearer's arm may be shown, I have illustrated a simple and easily adjustable means for so doing, by which the wearer may put on or remove the protector without effort. To this end, one or more outwardly facing spring eyelets 14 are 35 secured along one lateral edge of the reinforcing member. Three of such eyelets are shown in the present instance secured in place by headed shanks 15 which extend through both the base and the reinforcing member. 40 The opposite side of the protector carries a like number of flexible straps 16 mounted thereon in positions corresponding to those of the eyelets 14 and secured thereto by means of rivets 17, or the like, extending through 45 both the base and the reinforcing member. Each of the straps carry a stud member 18 (Fig. 3) which, with one of the eyelets 14, forms a complementary snap fastener. The 50 studs 18 are preferably mounted for longitudinal adjustment along the length of the straps in the well known manner.

If more than one thickness of material is used in forming the base, the several thicknesses may be secured together by such means 55 as the marginal stitching 19 (Fig. 2).

It will be apparent from the foregoing description that I have provided a new and improved novel arm protector which possesses great wearing strength without being 60 cumbersome to the wearer. The wearing strength is enhanced by the advantageous manner of firmly and permanently uniting the reinforcing member with the base, where- 65 in the ventilating members 13, the shanks 15 of the eyelets 14, and the rivets 17 all serve

as securing means in addition to the stitching 11. Moreover, the protector is simple in construction and may be manufactured for sale at a low cost.

I claim as my invention:

1. An arm protector comprising, in combination, a base of material composed of substantially pure wool fibres and of sufficient size to encircle a wearer's arm and position the ends in overlapping relation, a reinforcement for the exposed surface of said base comprising a sheet of material having a plurality of small metallic members dispersed about the surface thereof, centrally apertured eyelets extending through said base and reinforcement for ventilating said protector and for securing said reinforcement and base together, means for detachably securing said protector in place on a wearer's arm, and means for attaching said securing means to said base, said latter means also extending through said base and reinforcement additionally to secure them together. 70 75 80 85

2. An arm protector for preventing injury to a wearer comprising, in combination, a base of woven material composed of substantially pure wool fibres and of sufficient size to encircle a wearer's arm and position the ends in overlapping relation, a reinforcing member for the exposed surface of said base, means for detachably securing said protector upon a wearer's arm including parts extending through said base and reinforcing member to secure said base and member together, and ventilating eyelets spaced about the surface of said reinforcing member and also extending through said base and member. 90 95 100 105

3. An arm protector comprising, in combination, a base adapted to encircle a wearer's arm formed of a woven cloth-like material composed of substantially pure-wool, fibres, a reinforcing sheet permanently secured to said base, a plurality of small metallic armoring devices fixed to said reinforcing sheet for presenting a wearing surface adapted to resist the cutting and tearing action of sharp-edged articles, a plurality of means defining ventilating apertures about the reinforced body of said protector, and means for securing said protector in position upon a wearer's arm, said aperture defining means and said securing means being arranged to extend through said base and sheet to secure said parts permanently together. 110 115 120

In testimony whereof, I have hereunto affixed my signature.

KARL E. JENSEN.
